PACKING BOX FOR GOODS, AND MORE PAR-
TICULARLY FOR DELICATE GOODS

Lage Ragnar Henrik Hellman, Vasteras, Sweden

Application January 4, 1933, Serial No. 650,077
In Sweden September 12, 1931

6 Claims. (Cl. 229—14)

This invention relates to certain new and useful improvements in packing boxes for packing goods, and more particularly to packing boxes for packing delicate goods such as glass, instruments and the like, and its particular object is to obtain an improved device in such packing boxes in order to prevent shocks and blows on the packings from being transmitted to the packed goods; another object of this invention is to make it possible to store the cartons in stores and during transport in a suitable manner.

More particularly the invention has for its object a packing box consisting of an outer carton of corrugated cardboard, pasteboard, and the like, and an interior carton of the same material, located in the outer carton at some intermediate space from the walls of the outer carton. In the intermediate space are provided resilient or yielding spacer members integral with, or provided on the walls of one carton, or of both cartons, said spacer members being adapted to abut against the other carton. Preferably the spacer members consist of ribs of corrugated cardboard, pasteboard, wood or the like secured to the walls, top and bottom of the interior carton, said ribs serving to receive shocks et cetera on the outer carton, for which purpose the ribs are of such a size that they can abut against the outer carton. Thus special loose fillers, such as wood fibre, sawdust, paper strips, or fillers of other material, are unnecessary.

A further feature of the packing box comprising an outer and an interior carton as stated above is that the two cartons are collapsible or foldable at their edges and provided with top and bottom cover members adapted to be opened and closed so that when open the cartons may be flattened with the sides of the carton lying against each other, in order to facilitate the storing and transport of the cartons.

The above and other objects of the invention will appear from the following description, and be illustrated in the accompanying drawings, in which:

Figure 1 is a perspective view of an embodiment of the invention with the interior carton a little drawn out;

Figure 2 is a section along the line II—II of Figure 1; and

Figures 3 and 4 are the outer and the interior carton respectively, with the top and bottom covers folded out, and the cartons in a partly flattened position;

Figure 5 is a view corresponding to Figure 2 of a somewhat modified embodiment.

In the embodiment shown in Figures 1—4 the two cartons constituting the packing box, the outer 2, as well as the interior 3 located in the outer carton at some distance from the walls of the outer, consist of a sheet of corrugated cardboard, pasteboard or the like, the said sheet being folded along three cuts 4 or the like, and with its end edges secured to each other by means of rivets 5, tacks, paste tape or the like so that the carton obtains a rectangular cross section, the cuts and the connection line respectively forming the edges of the carton. On line with the cuts the carton sheet is slit on both sides so that four flaps or lids 6 are formed on each side, said flaps being foldable along cuts 4a toward the 15 respective opening of the carton in order to form the top and bottom cover respectively, two opposite flaps being folded preferably edge against edge, and the other two being folded over the first-mentioned flaps and secured to each other. 20 When the flaps are folded out the carton may consequently be flattened as indicated in Figures 3 and 4.

Of course, the respective carton may also be designed in another way, for example with a triangular or other (pentagonal, hexagonal et cetera) section, and, if desired, be composed of several parts secured to each other by means of paste tape, tacks et cetera. The flaps are then arranged in a suitable manner so that they can be folded for the indicated purpose.

On the outside of the walls 7 of the interior carton and on two opposite, i. e. outer flaps 6 are secured a number of ribs 8 or the like, in the example two on each wall and on each flap respectively, running at right angles to the cuts and slot edges respectively, said ribs consisting of corrugated cardboard, pasteboard, fibres, wood and the like, and being secured to the carton by means of paste tape 9 or in another way (rivets, tacks et cetera). Preferably the ribs shown in the embodiment may consist of a number of superposed pasteboard strips. If desired, the ribs may be integral with the carton by pressing or folding them out from parts of the walls of the carton. 40 The ribs which serve as spacer members between the interior and the outer carton are of a size to conform to the space between the cartons so that when assembling the packing box the spacer members will abut against the outer carton, and thus receive the shocks and blows to which the outer carton is subjected, and prevent said shocks and blows from being transmitted to the packed article by the, to a certain extent, resilient walls et cetera of the interior carton, and more- 55

over they increase the resistance of the packing to outer pressure. Of course, the number of the ribs is determined by the size of the carton, the weight and appearance of the article to be packed et cetera. The ribs are disposed at such a distance from each other that the shocks et cetera are not transmitted directly to the interior carton. Further they should be placed so as to facilitate the insertion of the interior carton in the outer carton, and consequently parallel to the insertion direction.

Preferably after the bottom cover of the interior carton has been closed, with the rib-provided flaps outermost and joined by means of paste tape, or in some suitable, preferably easily detachable way, the article in question is packed in the carton, and then the top cover is closed in the indicated manner. Then the interior carton is introduced into the outer carton subsequent to the bottom of said outer carton having, if desired, been closed according to the manner indicated above, whereby the cartons preferably should be so dimensioned relatively to each other that the sides glued together or fixed in some other way, i. e. the cover and bottom of the interior carton, will be placed against whole sides (i. e. wall portions) of the outer carton. Thus the resistance of the packing to outer pressure is increased.

Figure 5 is a modified embodiment in which the ribs 8 are triangular with one of the small sides provided with a flange-shaped continuation 10 to increase the fixing surface. The other features of the embodiment agree with that of Figures 1-4.

This invention includes the following great advantages: the risk that shocks and blows on the outer carton are transmitted to the packed article is greatly reduced; the packing is very resistant to outer pressure; further when the spacer members are rigidly secured to the interior carton only two elements are at hand (thus, as a rule, no loose interior fillers which are hard to adjust and retain in their places); the packing and mounting operation is considerably facilitated; the spacer members can be exactly held in suitable positions; due to the foldability of the cartons their packing and storing in stores and during transport likewise are facilitated.

Of course, the above embodiments are only

chosen as an example to explain the invention, and a great many variations are possible without going beyond the scope of the invention. Thus the ribs may be secured to the insides of the outer carton, or be pressed out on said insides instead of on the interior carton, or said ribs may be provided or pressed out on the interior as well as on the outer carton.

Having now described my invention, what I claim as new and desire to secure by Letters Patent is:

1. A packing box comprising an outer carton, an inner carton disposed therein, both the inner and outer cartons being provided with top and bottom flaps, and spacing means carried by the body and the top and bottom flaps of the inner carton to keep the cartons in spaced relation with respect to each other.

2. A packing box as claimed in claim 1, in which the said spacing means are disposed on the inner carton along lines parallel to the creases formed at the base of the flaps.

3. A packing box as claimed in claim 1, in which the said spacing means consist of oblong bodies disposed on the inner carton parallel to the creases formed at the base of the flaps, the said inner carton being so constructed that its flaps face the side walls of the outer carton when nested therein.

4. A packing box comprising an outer carton, an inner carton disposed therein, each of said cartons comprising four side walls, a pair of flaps extending from each side wall to form end walls, whereby each end wall is formed by a set of four flaps, two oblong spacing members attached to each side wall of the inner carton and one oblong spacing member attached to each of two oppositely disposed flaps of each set of flaps of the inner carton, all the said oblong spacing members being disposed parallel to each other and the creases formed at the base of the flaps.

5. A box as claimed in claim 4, in which said inner carton is so constructed that its flaps face the side walls of the outer carton when nested therein.

6. A box as claimed in claim 4, in which each of said cartons is made of a one-piece blank adapted for flat folding.

LAGE RAGNAR HENRIK HELLMAN.
